Primary Examiner—Philip Hyder(74) Attorney, Agent, or Firm—Fredrikson & Byron, P.A.(57) CLAIM

I claim the ornamental design for a travel organizer, as shown and described.

DESCRIPTION

FIG. 1 is a perspective view of my new design for a travel organizer;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 6 Drawing Sheets*Fig. 1*Fig. 2Fig. 3*Fig. 4Fig. 5Fig. 6Fig. 7*
